UNITED STATES PATENT OFFICE.

AQUILLA G. OSSMAN, OF BUCYRUS, OHIO.

IMPLEMENT FOR EDGING OR TURNING BRICKS.

SPECIFICATION forming part of Letters Patent No. 336,820, dated February 23, 1886.

Application filed October 14, 1885. Serial No. 179,893. (No model.)

To all whom it may concern:

Be it known that I, AQUILLA G. OSSMAN, a citizen of the United States of America, residing at Bucyrus, in the county of Crawford, 5 in the State of Ohio, have invented a new and useful Implement for Edging and Turning Bricks, of which the following is a specification.

My invention has relation to improvements 10 in implements for edging and turning bricks on the drying-floor; and the object is to provide an implement by which the bricks or forms may be turned up from their flat sides onto their edges more expeditiously than by 15 hand or by the implements heretofore used for the purpose; and the invention consists in a support or frame having a handle and provided with a series of depending cross-pieces secured across the supporting piece or 20 frame, said cross-pieces being arranged at proper distances apart to set with one face against the bricks as they may be disposed on the drying-floor, whereby a number of bricks can be turned from their flat sides onto their 25 edges.

My invention further consists in the novel arrangement, construction, and combination of parts, as will be hereinafter more fully described, and specifically pointed out in the 30 claims made hereto.

I have fully and clearly illustrated the invention in the accompanying drawings, forming a part of this specification, and wherein—

Figure 1 is a perspective view of the implement, showing it applied to a number of bricks. Figure 2 is a similar view showing the bricks turned on edge. Fig. 3 is a front view of one of the cross-pieces. Fig. 4 is a 35 central vertical section thereof, and Fig. 5 shows a primary construction of the implement.

Like parts in the drawings are identified by the same letters of reference.

The letter A designates the support or frame, which may be of light metal, and consists of a bar bent into U shape, the side bars being parallel to each other, and on this part A are secured or fitted a number of cross-pieces, A', arranged at such distances apart 40 as to set over the bricks as they are generally disposed on the drying-floor.

In the preferred construction shown in Figs. 1 and 2 the frame consists of a small 45 round metal bar, A, bent into U shape, and

the cross-pieces A' fitted thereto. The cross-pieces A' consist of a thin metal plate, a, of about the length of a common brick and not so deep as the thickness of the bricks, and formed with a lip or ridge, a', extending 60 along the lower edge on that side intended to set against the brick. Apertures a'', to receive the bars of the frame, are made in the cross-pieces, and on the top are formed vertical studs or stems a'', which are screw-threaded to receive threaded nuts, washers a''' being fitted over the stems, whereby the cross-pieces are clamped to the bars in any desired arrangement.

The letter B designates the handle, having 70 a cross-head, b, with eyes at the ends to fit over the screw-studs on the cross-pieces, and is secured in place by the nuts, substantially as shown. A brace-rod, b', is pivoted to the cross-bar at the head of the frame, and has its 75 free end projected through an eye, b'', set in the handle. This brace-rod permits the handle, when set on any cross-piece, to be braced thereto by the adjustability of the rod through the eye on the handle.

The operation is readily perceived by inspection of the drawings. The implement is set over a number of bricks and pulled with sufficient force in the direction of the hand to turn the bricks on edge.

What I claim as my invention, and desire to secure by Letters Patent, is—

1. The implement for edging bricks herein described, consisting of a supporting piece having a number of depending cross-pieces 90 rigidly secured thereto and provided with a handle, substantially as described.

2. The implement for edging bricks, consisting of a support or frame, a series of depending cross-pieces adjustably secured thereto, and an adjustable and detachable handle, 95 substantially as described.

3. The frame A, bent into U shape, the depending adjustable cross-pieces A', clamped thereto, the handle B, having a cross-head 100 formed with eyes in the ends, and the adjustable brace-rod b, all combined substantially as described, and for the purpose stated.

In witness whereof I have hereunto set my hand in the presence of two attesting witnesses.

AQUILLA G. OSSMAN.

Attest:

S. W. BENNETT,
JNO. A. EATON.
